BOILER FURNACE

Frederick W. Riehl, Denver, Colo.

Application August 16, 1937, Serial No. 159,293

8 Claims. (Cl. 122—135)

This invention relates to an apparatus for heating and more particularly for heating dwellings by means of steam, hot water or other heating medium.

5 This application is a continuation in part of application Serial No. 715,647, filed March 15, 1934, now Patent No. 2,092,334, granted Sept. 7, 1937.

10 The prior application discloses a boiler furnace comprising a more or less vertical combustion chamber on which is mounted a horizontal container for the fluid heating medium to be heated by the furnace, the container having end compartments and a mid compartment spaced 15 apart, by flue spaces and adapted to receive the fluid medium, a plurality of flue passages thru said mid compartment connecting the flue spaces on either side, a tube for heating fluid medium extending thru each passage and each of said 20 flue spaces and connected into the end compartments of said container and a plurality of flue tubes extending from the flue space on one side of said mid compartment above the other flue space, to and thru the opposite end wall of the 25 container, said other flue space opening into the combustion chamber.

30 In accordance with the disclosure of the said prior application the hot combustion gases from the combustion chamber pass into the flue space connected therewith, thru the flue passages and around the fluid medium tubes into the opposite flue space, and then thru the flue tubes by which the gases leave the container and furnace proper. Provision was also made for preheating air with 35 the flue gases discharged from the container.

40 The primary object of the present invention is to provide certain improvements in the container, the combustion chamber and the cycle of water or fluid flow in the apparatus of the prior application.

45 Other objects, features and advantages of the invention will be apparent from the following more detailed description thereof taken in connection with the accompanying drawing in which Fig. 1 is an elevational view of the improved furnace partly in broken section.

50 Fig. 2 is a vertical cross sectional view of the upper portion of the furnace structure shown in Fig. 1 taken on the central section line shown in Fig. 1.

55 Fig. 3 is a broken vertical view of the lower portion of the furnace shown in Fig. 1 showing an added feature.

Referring to the figures of the drawing the furnace or heating apparatus comprises a lower

boiler section 2 and an upper boiler section 4. The lower section 2 includes a vertical combustion chamber within a water jacket formed by inner and outer walls 6 and 8. Relatively cool water or other fluid to be heated is introduced 5 at the bottom of the water jacket and is forced to pass therethru in a spiral path by a spiral partition or fin 10 mounted between the walls 6 and 8 as shown.

The combustion chamber in the section 2 is 10 supplied with hot combustion gases from burners mounted in the bottom. The burners preferably comprise an inner annular gas burner 12 of the usual Bunsen type as shown, and an outer annular burner 14 which is preferably supplied only 15 with gas so that a long luminous flame will be provided along the wall 6 so that the long flame provides ample radiant heat for heating the entire wall 6. The Bunsen flame from the center burner supports the flame temperature of the 20 outer raw gas burner thereby giving perfect combustion and at the same time placing a luminous flame along the inside of the lower boiler section to permit the maximum amount of radiant 25 heat to face the black side wall 6. This method of heating avoids the necessity for any refractory to support flame temperature and permits 30 perfect control of the luminous flame.

The luminous flame becomes very long and gives 35 a large surface of white flame which gives up a 30 large amount of radiant heat to the lower boiler section so that it functions as a flash boiler.

The upper section 4 of the apparatus rests in the saddle-like top of the section 2 and the two 40 may be secured together if desired. The hot 35 combustion gases from the combustion chamber of the section 2 enter the upper section 4 through a flue space 16 and pass thru horizontal 45 flue passages 18 into a second flue space 20. The flue gases then leave the space 20 thru flue tubes 22. The walls forming the flue spaces 16 and 20 50 form partitions which divide the container 4 into three water compartments, and compartments 24 and 26 and a middle compartment 23. When the 55 apparatus is used as a steam generator or boiler the water level is held slightly above the tubes 22. A guage glass is provided to indicate the level.

In the operation of the apparatus the steam and hot water produced in the lower section 2 60 pass thru a conduit 30 into end compartment 26 of the upper section 4 where the steam separates 65 and leaves the container 4 thru a steam line 32 for distribution to house radiators or other point of use. The construction is preferably such that 70 the lower section 2, as well as the compartment 55

26 receive water in the proper ratio to the heating so that they function as flash sections. The water passed into compartment 26 flows thru tubes 34 in an upward direction into end compartment 24 from which it flows over the walls of flue space 16, around flue tubes 22 and into the middle compartment 28. The bottom of the compartment 28 is provided with an outlet pipe 36 thru which water flows down to the lower part 10 of the water jacket 2 between the walls 6 and 8. The water makes a complete cycle thru the lower and upper sections of the apparatus, passing generally concurrent to the combustion gasses in the lower section and countercurrent in the upper 15 section.

Water or other fluid to be heated is preferably supplied to the apparatus thru an inlet pipe 38 which connects into the pipe 36. The water jacket section 2 and the compartment 24 are provided with drain connections (not shown). Compartments 26 and 28 drain thru pipes 30 and 36 respectively into the jacket section 2 when it is drained.

The water capacity of the upper and lower 25 sections of the apparatus is preferably as low as possible so that it will be unnecessary to heat a large body of water before steam is generated. Accordingly the flues in the container 4 are preferably made as large as possible and of such 30 shape as to keep the water capacity to a minimum. For example flue passages 18 as shown in section in Fig. 2 are constructed in rectangular shapes or shapes which parallel to a great extent the wall of the container 4. This type 35 of construction decreases the water capacity of the container.

When the apparatus is used for house heating purposes it is preferably operated automatically from a house thermostat which starts and 40 stops the burners. When a demand is made for heat it is highly desirable that steam be supplied to radiators before the temperature in the house drops appreciably.

The furnace is provided with an arrangement 45 for supplying steam quickly by heating the condensate from the radiators. In Fig. 1 of the drawing condensate from the house radiators is returned thru a line 40 to a small flash boiler 42 mounted in the outlet flue from 50 the furnace as shown. The condensate enters an upper header 44 and flows into a plurality of finned heating tubes 46 which connect into a lower header 48. The tubes 46 are mounted directly in the path of the hot flue gases from 55 the flue tubes 22. Excess condensate above a certain level in the flash boiler 42 flows thru a bent pipe 50 into the pipe 36 and enters the bottom of the section 2. The level in the tubes 46 will be approximately that in the container 60 4 or higher, depending on the height of the bend in pipe 50. Flue gases pass from boiler 42 thru a flue 52 to a stack (not shown). Steam is formed in the tubes 46 very quickly after the burner starts and it is conducted to radiators 65 thru a steam line 54 (which may connect into the line 32) long before steam is available from sections 2 or 4 of the furnace. When the burner first starts up there is no condensate being returned from the radiators so that the water in tubes 46 is not cooled by the entrance of cold water. In the later operation condensate is preheated in the boiler 42 before it reaches the section 2.

When the furnace is used as a steam boiler for 70 heating a house, domestic hot water is preferably

heated in a jacket tank 56 which may be welded to the top of the section 4 over the steam space as shown. Water is supplied to the jacket tank 56 thru a pipe 58 and withdrawn hot thru a pipe 60. When the apparatus is used to heat a house with hot water the cold water return line may connect into the line 40 (the line 54 not being used) so that the relatively cold water is preheated by the flue gases leaving the furnace. Furthermore the domestic water is 10 preferably heated by the furnace in the manner shown in Fig. 3 in which only a portion of the apparatus of Fig. 1 is shown. In Fig. 3 the section 2 is provided with a water heating jacket 62 which is welded onto the outside of the wall 15 2. Water is supplied to the jacket 62 by a line 64 and withdrawn thru a line 66. In using the furnace to heat a house with hot water a higher temperature domestic water can be obtained by 20 using the heater 62 in Fig. 3 than the tank 56 of Fig. 1.

From the foregoing description of the invention it will be apparent that various changes and modifications may be made in the apparatus and its operation without departing from the spirit and scope of the invention. For example the apparatus is preferably of welded boiler steel but may be made of cast metal. Instead of using a stack to take the flue gases they may be drawn thru a suction fan and discharged thru an ordinary 3 or 4 inch pipe. The suction on the furnace should be controlled so that the proper proportion of air will be drawn in around the burners to give the desired combustion as described above. The whole apparatus should also be insulated altho no insulation is shown in the drawing. It is also understood that provision for cleaning various tubes and flues may be made within the scope of the invention. The steam as well as the excess condensate from the flash boiler 42 may be passed directly into the steam space of section 4 so that it is not necessary to have lines 50 and 54.

Having described the invention in its preferred form what is claimed as new is:

1. A steam boiler furnace, comprising upper and lower sections for heating water to produce steam, the lower section including a substantially vertical combustion chamber inside an annular water jacket, and a spiral partition in the jacket to provide a long path for water travel, said upper section including a substantially horizontal container for water and steam containing a middle and two end compartments interconnected for passage of water and formed by two interconnected walled flue spaces extending across said container, one of said spaces opening into said combustion chamber and the other being connected for gas flow with an exhaust flue gas box at one end of said container, and water conduits connecting one end and the middle compartments of the upper section respectively with the top and bottom of the water jacket of the lower section of said boiler furnace.

2. A steam boiler furnace as defined by claim 1 in which said walled flue spaces are spaced a substantial distance apart and connected by a relatively large angular shaped flue passage, and a plurality of tubes for water extending thru said flue spaces and connecting said end compartments.

3. A steam boiler furnace as defined by claim 1 in which said walled flue spaces are spaced apart to form said middle compartment and are connected by a plurality of relatively large flue

passages, and a plurality of tubes for water flow extending thru each flue passage and interconnecting the said end compartments.

4. A steam boiler furnace as defined by claim 5 1 in which the connection between said exhaust flue gas box and the walled flue space connected therewith comprises a plurality of flue tubes having a substantial surface in said container and which extend from said flue space, above 10 the walls of the flue space connected with said combustion chamber and discharge into said exhaust box.

5. A steam boiler furnace as defined by claim 1 in which a condensate flash boiler element is 15 mounted in said exhaust flue gas box and adapted to be heated by hot flue gas discharged from said container, means for delivering condensate to and for conducting steam from said condensate flash element, and means for conducting 20 excess condensate from said element to the lower portion of the jacket of said lower furnace section.

6. In an apparatus for heating liquids with hot gases of combustion, upper and lower furnace sections for heating liquids, the lower section 25 including a substantially vertical combustion chamber inside an annular water jacket, said upper section including a substantially horizontal container containing a middle and two end compartments interconnected for passage of 30 liquid and formed by two interconnected walled flue spaces extending across the lower portion of said container, one of said spaces opening into said combustion chamber and the other being connected for gas flow with an exhaust 35 flue gas outlet at one end of said container, a plurality of angular shaped relatively large flue gas passages extending through said middle compartment and connecting said flue spaces, said passages being of such size and so shaped as to

provide relatively little liquid capacity between each other and between the passages and the lower wall of said middle compartment whereby the volume of liquid in said middle compartment will be relatively small compared to the heating 5 surface provided by said flue gas passages and flue spaces, and a conduit connecting said upper and lower sections for flow of liquid.

7. A steam boiler furnace comprising upper and lower sections for heating water to produce 10 steam, the lower section including a substantially vertical combustion chamber inside an annular water jacket, said upper section including a substantially horizontal container for water and steam containing a middle and two end compartments interconnected for passage of water 15 and formed by two interconnected walled flue spaces extending across the lower portion of said upper section, one of said spaces opening into said combustion chamber and the other being 20 connected for gas flow with an exhaust flue gas box at one end of said container, a condensate flash boiler element mounted in said exhaust flue gas box and adapted to be heated by hot flue gases discharged from said container, means 25 for delivering condensate to and for conducting steam from said condensate flash boiler element, means for conducting excess condensate from said element to the lower portion of the jacket of said lower furnace section, and means for conducting water from said lower section to the 30 upper section of said boiler.

8. A steam boiler furnace as defined by claim 1 in which said walled flue spaces extend across only the lower portion of said upper section 35 thereby providing an open steam space in said upper section above said compartments.

FREDERICK W. RIEHL.
